(57) **CLAIM**

I claim, the ornamental design for a television receiver, as shown and described.

DESCRIPTION

FIG. 1 is the front perspective view of a television receiver showing my new design;

FIG. 2 is a front elevation view thereof;

FIG. 3 is a rear elevation view thereof;

FIG. 4 is a side elevation view thereof;

FIG. 5 is another side elevation view thereof;

FIG. 6 is a top plan view thereof;

FIG. 7 is a bottom plan view thereof; and

FIG. 8 is an enlarged view of the circled area A shown in FIG. 2;

FIG. 9 is an enlarged view of the circled area C shown in FIG. 6; and,

FIG. 10 is an enlarged view of the circled area B shown in FIG. 5.

The surface treatment of the television receiver shown in the figures forms no part of the claimed design, a television receiver according to the claimed design may have any surface treatment.

The broken lines illustrating portions of the television receiver are for environmental purposes only and form no part of the claimed design.

1 Claim, 10 Drawing Sheets
